UNITED STATES PATENT OFFICE.

WILLIAM SHAW, SR., OF ESMOND, RHODE ISLAND, ASSIGNOR OF ONE-THIRD TO
WILLIAM SHAW, JR., OF ESMOND, RHODE ISLAND, AND MANUEL E. SOUZA, OF
FALL RIVER, MASSACHUSETTS.

SPINNING MACHINE.

Application filed January 6, 1923. Serial No. 611,045.

To all whom it may concern:

Be it known that I, WILLIAM SHAW, Sr., a citizen of the United States, residing at Esmond, in the county of Providence and

5 State of Rhode Island, have invented certain new and useful Improvements in Spinning Machines, of which the following is a specification.

This invention relates to spinning machines and more particularly to novel means 10 for winding the roving on the bobbins in fly frames and the like, and the primary objects of the invention are first, to provide means for eliminating all strain on the cone 15 belt, second, to provide means for shifting from equal speed of the drive shaft and bobbin drive gear to excess speed and vice versa, and third, to make the cone into a driven member instead of a drive member, 20 to permit the carrying out of the various features of the invention.

It is a further object of the invention to provide means for revolving the bottom cone in the opposite direction to that when the 25 frame is running, when it is desired to wind the roving on the bobbin.

A still further object of this invention is to provide an improved differential mechanism for spinning machines, of the above 30 character, which will be durable and efficient in use, one that will be simple and easy to manufacture, and one which can be incorporated in spinning fly frames at a minimum cost.

35 With these and other objects in view the invention consists in, the novel construction, arrangement and formation of parts, as will be hereinafter more specifically described, claimed and illustrated in the accompanying drawings, forming a part of this specification, in which drawings:

Figure 1 is a fragmentary elevation showing the improved differential mechanism incorporated with a fly frame, parts of the 45 differential mechanism being shown in section.

Figure 2 is a detail section taken on the line 2—2 of Figure 1 looking in the direction of the arrow.

50 Figure 3 is a detail section taken on the line 3—3 of Figure 1 looking in the direction of the arrow.

Figure 4 is a detail section taken on the

line 4—4 of Figure 1 looking in the direction of the arrow, and

Figure 5 is a detail section taken on the line 5—5 of Figure 1.

Referring to the drawings in detail, wherein similar reference characters designate corresponding parts throughout the several views the numeral 10 indicates the main drive shaft, having a pinion 11 keyed to one end thereof, which is adapted to mesh with an idle pinion 12, having contact with the drive pinion 13. This drive pinion 13 is keyed or otherwise secured to the top cone shaft 14, on which is mounted in any preferred way the usual top cone 15. The bottom cone 16 is of course similar to the top cone 15 and has the apex or tapered portion thereof disposed opposite to the tapered or apex portion of the top cone 15. The bottom cone 16 is mounted upon a suitable shaft 17 carrying a relatively large spur gear wheel 18, which in turn meshes 70 with a relatively small spur gear wheel 19 which is keyed or otherwise secured to the lower cone driven shaft 20.

The end of the drive shaft 10 opposite to the spur gear 11 has keyed or otherwise secured thereto a spur gear 21 utilized for driving the spindles. Rotatably mounted 80 upon the drive shaft 10 inward of the gear 21 is a differential sleeve 22, which has keyed or otherwise secured thereto a spur gear wheel 23, which is utilized for driving the bobbins. The gear 21 and the gear 23 are of

substantially the same diameter and are provided with the same number of teeth. The inner end of the sleeve 22 is provided with 85 a cylindrical-shaped housing 24 which has formed on its inner surface an internal ring gear 25, which can be considered in this instance as having forty-eight teeth. A cross

piece 26 is keyed to the main drive shaft 90 10 and disposed within the cylindrical housing 24 and has its opposite terminals supporting outwardly extending studs 27, on which are rotatably mounted gears 28 and

29 and gears 30 and 31. The gears 28 and 95 29 can be considered as having sixteen teeth, while the gears 30 and 31 can be considered as having thirty teeth. The gears 28 and 29 mesh with the internal ring gear 25, while the gears 30 and 31 mesh with a gear 100 32, which can be considered as having eight-

een teeth and this gear can be keyed or otherwise secured to second differential sleeve 33 rotatably mounted upon the drive shaft 10.

- 5 Splined to the second differential sleeve 33 is a sliding differential sleeve 34, which has secured to its inner end a large spur gear 35, which meshes with a relatively small pinion 36, which is keyed to the inner end of the lower bottom cone driven shaft 20. The opposite end of the sliding differential sleeve 34 from the sun gear or beveled gear 35 has formed thereon clutch teeth 37 for engagement with the teeth 38 of 10 a non-sliding clutch section 39, which is secured to the main drive shaft 10. The sliding differential sleeve 34 can be shifted by a suitable shifting yoke 40, which can be carried by a lever 41, which is rockably 15 mounted upon a suitable pin 42, that is to be secured to any preferred part of the frame. It can be seen that when the sliding sleeve 34 is shifted so that the teeth 37 will mesh with the teeth 38 of the non-sliding clutch 20 section 39 that the gear 35 will be moved out 25 of engagement with the pinion 36. The lever 41 has pivotally connected thereto at a point intermediate its ends a link 43 which is connected to the short arm of a bell crank 30 lever 44. This bell crank lever is rockably mounted at its angle upon a suitable pin 45 carried by any preferred part of the frame. A head 46 is pivotally connected to the outer 35 end of the long arm of the lever and has slidably connected thereto a rod 47 which is connected with a suitable collar 48 mounted upon the lower cone shaft 17 and it can be seen that when the lever 41 is actuated to 40 slide the sliding differential sleeve 34, that the bottom frame can be stopped and the bottom cone can be raised which is necessary to run over the ends for doffing. The slot in the head 46 gives ample space to permit the bottom cone to be lifted by hand without 45 making a disconnection, as described above, which is necessary at times when the end slackens and the bottom cone must be turned back to give the slack ends the proper tension.
- 50 It will be readily seen, that when the gear 35 is held stationary, the speed of the bobbin drives gear 23 will be increased one revolution for every five revolutions that the driving shaft 10 makes.
- 55 The operation is as follows: The cross piece 26 being keyed to the drive shaft 10, causes the gears 30 and 31 to circle gear 32 and assuming gear 32 as standing still, gear 23 will gain one fifth of a revolution. So it thus can be seen that bobbins are given 60 their highest speed when the gear 32 is stopped. Thus at the beginning of a set of rovings, when the bobbins are driven at their highest speed, the cone belt is on the small end of the top cone and on the large

end of the bottom cone, in a condition reversed from general up-to-date fly frames. When the cone belt is given a lateral motion at each change of the traverse, the speed of the bottom cone is increased, which 70 takes revolutions from gear 23 owing to the increased speed of the gear 32. When the set of rovings are completed, the cone 16 is raised and a disconnection is caused, the gear 35 being pulled out of mesh with the 75 gear 36 and a connection made between the sliding differential sleeve 34 and the non-sliding clutch section 39, which locks the whole mechanism as one piece and thus the gear 23 i. e. the bobbin drive gear and the gear 21, which drive the spindles revolves 80 the same speed and no winding takes place.

On fly frames of the usual construction, at times, when the bottom cone is raised, if the same is not held stationary by some 85 means, it will revolve in the opposite direction and make considerable trouble by breaking and tangling the ends. This statement of course bears out the fact that a great amount of resistance is exerted on the cone 90 belt.

It can be seen from the foregoing that this improved mechanism eliminates all of the above mentioned trouble, as a complete disconnection is made when the bottom cone 95 is raised.

The good working of the winding of the rovings on the bobbins depends largely upon the cone belt, and the strain on the cone belt is usually the factor which causes unequal 100 conditions on fly frames.

The improved devices relieves all the strain and friction on the cone belt, for the excess speed is obtained by the driving shaft, which will effectively hold the relationship 105 between the cones and the fliers (not shown).

It is to be noted that the top and bottom cones 15 and 16 respectively are connected by the cone belt 16', which can be shifted 110 in any preferred way.

Changes in details may be made without departing from the spirit or scope of this invention.

What I claim as new is:—

1. In a fly frame, a drive shaft, a spindle drive gear keyed to the shaft, a bobbin drive gear rotatably mounted upon the shaft, a top and bottom cone, means for driving the drive shaft and spindle drive gear and the 120 bobbin drive gear at the same rate of speed from the cones and means for driving the bobbin drive gear at an increased rate of speed in relation to the drive shaft and the spindle drive gear.

2. In a fly frame, a drive shaft, a spindle drive gear keyed to the shaft, a top and a bottom cone, driving connection between the top cone and the drive shaft, a cone belt for connecting the cones together, a rotatable 130

differential sleeve mounted upon the drive shaft, a bobbin drive gear keyed to said sleeve, a second differential drive sleeve rotatably mounted upon the shaft, a sliding differential sleeve feathered upon the second mentioned differential sleeve, a housing secured to the first differential sleeve, an internal ring gear carried by the housing, a cross piece keyed to the drive shaft and disposed within the housing, studs rotatably carried by the cross piece, gears carried by one terminal of each stud for engaging the internal ring gear, a spur gear keyed to the second mentioned differential sleeve, a spur gear connected to the other terminals of the studs for engaging the spur gear keyed to the second differential shaft, a driven shaft, means operatively connecting the lower cone with the driven shaft, 20 and a relatively large pinion carried by the sliding differential sleeve, a relatively small pinion carried by the driven shaft and meshing with the pinion, a clutch keyed to the second differential sleeve and means for moving the sliding differential sleeve for moving the relatively large gear from out of engagement with the small gear carried by the driven shaft and the sleeve in engagement with the clutch.

30 3. In a fly frame, a drive shaft, top and bottom cones, a cone belt for connecting the cones together, means for driving the drive shaft from the upper cone, a driven shaft, means connecting the bottom cone and the driven shaft together, a differential sleeve mounted upon the drive shaft, a bobbin drive gear carried by the sleeve, a second differential sleeve, a sliding differential sleeve feathered upon said second differential sleeve, a spur gear secured to the second mentioned differential sleeve, a cross piece secured to the drive shaft, spur gears carried by the cross piece, a housing rotatable with the first mentioned differential sleeve, a ring gear carried by the housing, the spur gears carried by the cross piece meshing respectively with the ring gears and with the spur gear carried by the second mentioned differential sleeve, a relatively large gear carried by the sliding differential sleeve, a relatively small gear connected with the driven shaft and meshing with the relatively large gear, a stationary clutch section formed on the drive shaft, a sliding clutch section formed on the sliding differential sleeve, and means for synchronously raising the bottom cone end for sliding the sliding differential sleeve for moving the clutch section carried thereby into engagement with the stationary clutch section and the relatively large gear out of mesh with the relatively small gear.

In testimony whereof I affix my signature in presence of two witnesses.
